METHOD AND APPARATUS FOR BEATING
PAPER PULP

Walter N. Sherwood, North Hoosick, N. Y.

Application September 10, 1934, Serial No. 743,318

9 Claims. (Cl. 92—25)

This invention relates to a method and apparatus for beating paper pulp.

The object of the invention generally is to reduce the pulp to the desired state of fineness within a minimum time, and with a minimum consumption of power.

The invention has as a further object, a beater in which the paper pulp is fed between the beater roll and the bed plate in the form of a sheet, and is provided with means for regulating the thickness or amount of stock flowing in the sheet from minimum to maximum.

A further object of the invention is the provision of means to effect agitation and mixing throughout substantially the entire mass of pulp in the beater.

The invention consists in the method herein-after set forth, and in the novel features and the combinations and constructions hereinafter set forth and claimed.

In describing this invention, reference is had to the accompanying drawings in which like characters designate corresponding parts in all the views.

Figure 1 is a plan view, partly in section.

Figure 2 is a longitudinal, sectional view taken on lines 2—2, Figure 1.

Figure 3 is a fragmentary end elevation of the beater roll with a contiguous portion of the bed plate in section.

Figure 4 is a fragmentary, sectional view through the feeding roll.

Figure 5 is a fragmentary view, partly in section, showing the method of securing the fly-bars to the beater roll.

Figure 6 is a fragmentary view showing the relative position of the bed plates and roll plates, the beater roll having progressed slightly further in the cycle of rotation than is shown in Figure 3.

Figure 7 is a view similar to Figure 6 showing the beater roll as rotated slightly further than in Figure 6.

My method consists generally of beating paper pulp in the presence of a liquid, feeding the mass in the form of a sheet between the beater roll and the bed plate, driving the beater roll at a high speed and thereby causing the sheet of pulp to be discharged at high speed from between the beater roll and the bed plate, and agitating substantially the entire mass in the beater.

I have shown, in the drawings, a preferred embodiment of the apparatus for carrying out the above method.

10 designates the beater tub which is constructed with a bottom 12 inclined downwardly

toward the front wall 13 of the tub. The bottom 12 is connected to the rear wall 14 by an ascending curved portion 15, and with the front wall 13 by a similarly curved portion 16.

17 designates the beater roll which is secured to the shaft 18, which is rotatably mounted in suitable bearings 19 which, in turn, are mounted upon the adjustable supports 20, whereby the beater roll 17 may be adjusted vertically in any well known manner. Attention is called to the fact that the beater roll 17 is of sufficient length to extend across the entire width of the beater tub 10, and is of comparatively small diameter, the lowermost portion of the periphery of the roll being spaced a considerable distance from the bottom 12 of the tub.

The beater roll 17 is provided with a plurality of groups of fly-bars. Preferably, each group consists of three bars. The center bar 25 is comparable to the ordinary roll bar, or fly-bar. The bar 25 is secured to the periphery of the beater roll in any well known manner, and as here shown, the bars 25 are secured to the roll 17 by the ear method of Jordon construction. The bar preferably is formed in two sections, and joined together at the periphery of the center head 26 of the beater roll. The inner ends of the sections of the bar 25 are formed with a male-female joint, as indicated in Figures 4 and 5. In addition, the abutting ends of the sections are provided with complementary slots to receive the retaining band 27. The inner ends of the sections may be further secured together by means of a bolt 28. To each side of the bar 25 is secured additional fly-bars 29, 30. The bars 29, 30 are arranged in spaced apart relationship from the center bar 25 by spacers 31, the group being secured together by a plurality of rivets or bolts 32. The beater roll 17 operates in a clockwise direction (Figure 3) and the bars 29 are accordingly arranged on the forward side of the bars 25. The outer edge of the bars 29 are chamfered, or relieved, as at 33, and the outer edges of the bars 25, 30 are square.

A bed plate box 35 is arranged in the beater tub 10 below the beater roll 17 and extends across the tub. Preferably, the bed plate box 35 is arranged to one side of the vertical axis of the beater roll. As here shown, Figure 3, the bed plate box 35 is arranged to the rear of the vertical axis of the beater roll. The bed plate box may be secured to, or supported by, the sides of the tub in any suitable manner.

36 designates the bed plate casting provided with lengthwise extending bosses or ribs to which

5

50

55

are secured bed plate bars 37, as by bolts 38. A group of narrower bars are rigidly secured to the bars 37, as by bolts 39, providing a plurality of groups of bed plate bars, each group being supported by the bars 37. Preferably, there are different numbers of narrow bars in each of the groups, the forward group containing fewer bars than the rear group. As here shown, the forward group comprises a bar 37 with two narrow bars secured on the forward side, and one narrow bar secured to the rear side, while the second group includes two narrow bars on each side of the bar 37, and the third group, to the left, Figure 3, includes five narrow bars arranged on each side of the bar 37. The narrow bars are arranged in spaced apart relationship from the bars 37, and from each other, in a manner similar to the bars 29, 30, on the beater roll 17, and the upper edge of each forward bar is chamfered similar to the outer edge of the bars 29. The groups of bed plate bars are also spaced apart from each other, the third group being spaced a greater distance from the second group than the second group from the first.

The fly-bars on the beater roll 17 and the bed plate bars extend parallel with the axis of the beater roll. The spacing and width of the groups of fly-bars on the beater roll is such, relatively to the spacing between the groups of bed plate bars and the width of the groups, that one group of fly-bars on the beater roll is always in contact with one group of bed plate bars, as indicated in Figures 3, 6 and 7. However, during certain portions of the cycle of the beater roll, a group of fly-bars on the beater roll is in contact with each group of bed plate bars, as indicated in Figure 6, and during other portions of each cycle of the beater roll, only one group of fly-bars on the beater roll is in contact with one group of bed plate bars, as indicated in Figure 7. Due to the fact that one group of fly-bars on the beater roll is always in contact with one group of bed plate bars, interlocking of the fly-bars and bed plate bars is prevented. The main bars 37, and also the smaller bars secured thereto, are preferably formed in sections, as are the bars 25. In the event that one portion, or section, of the bars 25 in the beater roll, or the bed plate bars, become damaged, it is only necessary to replace the damaged section. The reason for the construction and relative arrangement of the fly-bars and the bed plate bars will be explained hereinafter.

The bed plate box 35 is formed, or provided, on its forward side, with a suitable support 40. An adjustable dam 41 is pivoted to the support 40, as at 42. The adjustable dam 41 may be of any suitable construction, and is substantially the same width as the beater roll. That is, the dam 41 extends across the beater tub, the ends of the dam having a sliding contact with the inner sides of the tub. As here shown, it is formed hollow with a compartment 43 which may enclose a metallic tank, or container, to aid in the buoyancy of the dam, it being desirable to have the dam 41 float in the stock to aid in the adjustment of the dam. Suitable means is provided for maintaining the dam 41 in any one of a plurality of adjustable positions. As here shown, the sides 70 of the tub are provided with a plurality of set screws 44, which coact with the sides of the dam.

A guide plate 46 is arranged to receive the discharge of the stock from between the beater roll and the bed plate. The lower end of the 75 guide plate 46 is secured to and supported by the

rear wall 47 of the bed plate box 35, and is supported at its ends, or sides, by the sides of the beater tub. A roll 48 extends across the beater tub, and is arranged adjacent the upper edge of the guide plate 46, the purpose of which will be explained hereinafter.

The forward portion of the beater is provided with a movable fillet 52 which is secured to the forward end of the beater tub by any suitable means, as here shown, by a hinge 53. When the beater is being loaded, the fillet 52 is swung backwardly against the front edge of the tub, and while the beater is in operation, the fillet is swung forwardly into the position shown in Figure 2. The fillet 52 aids in directing the flow of stock over the upper edge of the dam 41.

The fillet 52 also prevents a dead corner, or spot, in the mass of stock. That is, a place in the stock where there is no circulation, or eddy currents are set up which result in holding the stock in the corner.

Frequently, paper pulp beaters are provided with washing screens which are generally, more or less in the form of a cylinder and operate on the top surface of the mass. Such washing screens occupy a considerable amount of room, and involve a considerable expenditure to install. Also, it involves considerable time to change the cylindrical washing screens for washing different consistencies of stock. I provide one or both side 30 walls of my beater with apertures 55 which are provided with suitable valves and connected to a drain, the apertures being located, as indicated in Figure 2. When it is desired to wash the stock, I employ a removable screen 56 which is supported by suitable guides arranged on the sides of the tub, and extends inwardly at an angle to the front wall 13 of the tub. During the operation of the beater, the stock is circulated at considerable speed under the bed plate toward 40 the front wall 13, and travels upwardly in the front compartment against the screen 56. This pressure in the upward flow of the stock is very effective in forcing the water through the screen 56, the dirty water being carried away through 45 the openings 55. Screens of different size wire mesh may be readily inserted as desired.

The upper rear portion of the tub is provided with a cover 60 provided with a curved ceiling 61, as indicated in Figure 2 of the drawings. A suitable cover 62 is also provided over the beating chamber. The covers 60, 62, are provided with suitable vents 63 due to the fact that the beating roll 17 operates at such high speed and resulting in the stock being discharged from the roll at 55 great speed, and with considerable force, I have found the vents prevent any back pressure in the beating chamber, or the first mixing chamber.

In operation, the beater tub 10 is filled approximately two-thirds full of water. The beater roll is rotated at comparatively high speed, preferably with a peripheral speed of 3000 to 4000 peripheral feet per minute. At this time, the dam 41 is lowered to the center dotted line position (Figure 2), or sufficiently low to permit a good supply of water to flow over the upper edge of the dam and between the beater roll and the bed plate. The paper stock is now added. The stock passes over the dam 41 and is drawn between the beater roll and the bed plate, it being understood that at the commencement of the operation, the beater roll is adjusted with suitable clearance between it and the bed plate. Because of the high peripheral speed of the beater roll, the water and paper stock is discharged tangentially from the 75

under side of the beater roll at the rear of the bed plate at an angle substantially the same as the guide plate 46. As the beater stock becomes processed, the beater roll is gradually lowered to 5 reduce the clearance between it and the bed plate.

On account of the high peripheral speed at which the beater roll 17 is operated, the stock is discharged or drawn from the roll at great speed and with considerable force upwardly along the 10 guide plate 46 and against the curved ceiling 61 of the cover 60. As the stock strikes the ceiling 61, it is directed through an arc and downwardly along the rear wall 14 of the tub mingling with the stock in the tub and creating a considerable 15 flow along the inclined bottom 12 toward the front wall 13 of the tub. This flow passes under the bed plate box 35, and because of the volume and weight of stock in the higher rear portion of the tub and because of the flow created by the 20 forced discharge of the stock against the ceiling 61 and downwardly, the stock is flowed forwardly into the tub under the bed plate box 35 and is carried upwardly by the ascending curved bottom portion 16 with considerable speed and force. 25 The stock then flows over the upper edge of the dam 41 in the form of a sheet, the thickness of the sheet depending on how far the top of the dam is submerged below the surface of the stock. As previously explained, the position of the dam 30 may be regulated, as desired. The stock travels in sheet form down the inclined surface of the dam and is forced in between the beater roll and the bed plate or into the spaces between the groups of roll bars, which act as buckets.

The forward champered bars 29 on the beater roll act as collector bars collecting the fibers of the stock and because of the champer on the coacting edges of the bars 29, and the forward bars in the groups of bed plate bars, the fibers are collected and drawn in between the groups of fly-bars and bed plate bars. The fiber stock is then acted upon in the usual manner by the remaining bars in the group of roll bars and bed plate bars. As the group C of roll bars passes over the first 40 group of bed plate bars, an appreciable amount of stock will be deposited in the pocket between the first and second group of bed plate bars. As these pockets are of appreciable width, the stock deposited in them is subject to mixing and agitation, due partly to the centrifugal force with which the stock is drawn into the pockets on account of the high peripheral speed of the beater roll. As the group C of roll bars passes over the first pocket in the bed plate, it accumulates a 45 new deposit of stock and the beating action between this group of bars and the second group of bed plate bars is repeated in a manner similar to the action between the group C of fly-bars and the first group of bed plate bars. This process is 50 repeated as the group of roll bars passes over the second pocket between the second and third groups of bed plate bars, with the result that the paper stock is acted upon three distinct times, 55 while it is passing between the beater roll and the bed plate. Due to the fact that the first coacting knives in each group of roll bars and the groups of bed plate bars are champered, the fibrous stock is drawn in between the groups of bars with less cutting and mutilation, and it is then crushed and molarized by the remaining bars in the groups.

The molarizing is effected by the action of the large bars 25, 37. The smaller bars secured to the rear sides respectively of the bars 25, 37, act

to retain the stock between the plates, while it is being molarized by the heavier bars 25, 37.

It is to be understood that the smaller bars also effect crushing and molarizing to a certain extent. It will be observed that as the stock passes between the beater roll and the bed plate, it is gradually processed to a finer state and due to the fact that the fiber stock is drawn in between the coacting bars by the champered outer bars of each group, the processing of the stock is effected with less cutting and mutilation of the fibers.

As here shown, the successive groups of bed plate bars contain a greater number of bars, so that the stock is further reduced, as it is acted upon, by each successive group of bed plate bars.

It is to be understood that the bed plate structure may be such as to include any number of groups of bed plate bars desired. Due to the varying widths of the groups of bed plate bars and the varying distances between the groups, the power required to operate the beater roll varies during various portions of the cycle of the roll. As previously explained, at one period of the cycle, only one group of roll bars will be acting upon the stock and during another period of the cycle, three groups of roll bars may be acting upon the stock. Accordingly, this arrangement is particularly advantageous in producing finely beaten stock and is accomplished without any appreciable increase in the application or consumption of power.

The dam 41 and the adjustability thereof are important features of my invention. Due to the fact that the stock is fed to the beater roll in the form of a surface flowing sheet, and accordingly, the beater roll does revolve in the mass of the stock, the power applied to the beater roll is used entirely to effect the molarizing of the stock.

It is well known to those skilled in the art that in the usual beater, a considerable amount of power is consumed, because of the resistance encountered by the roll in revolving in the mass of stock. Also, by adjusting the dam 41, the thickness of the surface flowing sheet to the beater roll may be varied, as desired, and maintained at a thickness or depth which will supply a volume of stock to the beater roll comparable to the bucket carrying capacity of the roll. 45 Also, by raising the dam, the flow to the beater roll may be completely stopped, which often is desirable, and in the event a foreign substance should through accident or otherwise get into the mass, the flow to the beater roll may be instantly stopped without the necessity of shutting down the machine and the foreign substance removed before serious damage has been done to the tackle. Often, after the mass of stock has been beaten to the desired degree, it so happens 50 that the beater can not be dumped, which normally means that the beater roll continues to idle in the stock due to the fact that there are very many other beaters in the mill which permits discontinuance of the power. With my 65 beater, the flow of stock to the beater roll can be readily stopped and the beater may be idle without consuming any appreciable amount of power.

Where it is desired to use a beater as a continuous or extracting beater, rather than a batch beater, a suitable extracting apparatus may be arranged at the rear portion of the cover 60. As here shown, a cylinder 70 is so arranged that a portion of the periphery thereof

extends within the cover 60 and is so positioned that the stock as it is discharged from the beater roll and redirected from the ceiling 61 strikes the cylinder 70 or passes against it. The 5 cylinder may be formed of a plurality of sections 71, 72, 73. The section 71 is solid, the section 72 formed with apertures or perforations, and likewise the section 73, however, the perforations being smaller than those in the section 10 72. By rotating the cylinder 70 so that either the section 72 or 73 projects inwardly, the paper stock is collected in the cylinder and conveyed from the cylinder, which is preferably formed with an open end, to a trough, and thence to a 15 stuffing chest of the paper machine.

The cylinder 70 is rotatably mounted in the brackets 74, and is provided with a convenient manual 75 for rotating the same. Plates 76 are secured to each end of the beater roll as by 20 screws 77. These plates are provided with a central aperture closely fitting the shaft 18. The purpose of these plates is to prevent the collection of pulp in foreign substances, such as strings and the like, from collecting and winding about the 25 shaft 18, and also act as a closure for the elongated opening 78 in the sides of the beater for effecting vertical adjustment of the roll. On account of the structure and shape of my beater, and the high speed at which the beating roll 30 is run, the beating time is reduced substantially one-half, and a thorough mixing of the stock is effected by the continuous agitation of substantially the entire mass of stock.

It will be observed, Figure 2, that the stock 35 travels rearwardly and upwardly as it is discharged from the beater roll, and is then redirected as it strikes the curved ceiling of the rear upper portion of the tub and the rear wall of the tub. The mass of stock is circulated in 40 the form of a loop with the beater roll operating in the upper run of the loop, and the lower run of the loop passing between the bed plate and the bottom of the tub. The rear portion of the 45 upper run of the loop, that is, the stock as discharged from the beater roll travels with extremely high velocity, and is thrown rearwardly and upwardly against the curved ceiling while the rest of the stock in the rear portion of the tub is in the form of a comparatively large mass 50 of pulp moving in the opposite direction, or toward the forward end of the beater. The upper rearwardly moving stream of stock traveling at high speed commingling with the lower forwardly moving mass of stock at slower speed 55 effects very efficient mixing, and the impetus, given to the large mass of stock in the rear portion of the beater by the high velocity stream discharged from the beater roll, keeps the entire 60 mass of stock moving in the form of a loop with additional mixing taking place at the forward end of the beater, as the lower end of the loop is directed upwardly and over the upper edge of the dam 41.

What I claim is:

1. A paper pulp beater comprising a tub having an upwardly extending rear portion provided with a curved ceiling adjoining the rear wall of the tub, a beater roll rotatably mounted in the 70 tub and extending across the width of the same, a bed plate arranged below the beater roll, a dam member pivotally mounted forwardly of the beater roll and operable to convey the paper pulp in the form of a flowing sheet to the beater roll, 75 a guide plate arranged to the rear of the beater

roll for directing the paper pulp discharged from the roll upwardly and rearwardly against the curved ceiling of the tub, the bottom of the tub being inclined downwardly toward the front and being connected to the rear and forward walls 5 by ascending curved portions.

2. In a paper pulp beater comprising a tub, a beater roll rotatably mounted in the tub and extending across the width of the same, the tub being formed with an upwardly extending rear portion provided with a curved ceiling merging with the rear wall of the tub, a bed plate arranged below the beater roll, and a guide plate arranged to the rear of the beater roll and extending upwardly and rearwardly for directing 10 the pulp discharged from the beater roll against the curved ceiling portion, and means arranged adjacent the upper rear portion of the tub for collecting and conveying the beaten pulp out of 15 the tub.

3. A paper pulp beater comprising a tub, a beater roll rotatably mounted in the tub, a bed plate arranged beneath the beater roll, a guide plate extending upwardly from the bed plate to the rear of the beater roll to control the paper 25 pulp discharged from the beater roll, a roller arranged transversely of the tub and coating with the upper edge of the guide plate, and means for manually rotating said roller.

4. A paper pulp beater comprising a tub, a beater roll rotatably mounted in said tub, a bed plate arranged beneath the beater roll, the tub being provided with an upwardly extending rear portion having a curved ceiling, a guide plate arranged to the rear of the beater roll and extending from the bed plate toward the curved ceiling, a roller arranged transversely of the tub adjacent the upper edge of the guide plate, and being spaced apart from said curved ceiling, whereby the paper stock discharged from the beater roll 40 travels upwardly over the surface of the guide plate and is thrown beyond the roller against the curved ceiling of the rear portion of the tub.

5. A paper pulp beater comprising a tub, a beater roll rotatably mounted in the tub between 45 the ends thereof and extending across the same, the rear portion of the tub being of appreciably greater height than the forward portion and being provided with a curved ceiling, a bed plate arranged below the beater roll, a flat guide plate 50 arranged in the tub with the lower end of said guide plate adjacent the rear edge of the bed plate and the upper edge terminating short of said curved ceiling and being arranged to direct the pulp discharged from the beater roll upwardly against said ceiling, the bottom of the tub being inclined downwardly toward the front and being connected to the front and rear walls with ascending curved portions.

6. A paper pulp beater comprising a tub formed with a rearward portion of appreciable height and being provided with a curved ceiling adjoining the rear wall of the tub, a beater roll mounted in the tub between the ends thereof and extending across the same, a bed plate arranged beneath the beater roll, a flat guide plate mounted in the tub and being inclined upwardly from the bed plate toward the upper rear portion of the tub, with the upper edge of said guide plate terminating short of the curved ceiling of said 70 rear portion of the tub, whereby the paper pulp is discharged from between the beater roll and the bed plate at high velocity, and is thrown upwardly against said curved ceiling.

7. A paper pulp beater comprising a tub, a bed 75

plate arranged in the tub and extending across the width of the same and being spaced above the bottom of the tub, a beater roll rotatably mounted in the tub above said bed plate, the tub 5 being provided with a rearward portion extending upwardly above the beater roll, a flat guide plate extending upwardly and rearwardly from the rear side of said bed plate, all whereby the paper pulp is discharged at high velocity from 10 between the beater roll and the bed plate tangentially toward the upper rear portion of the beater tub and through space against said upper rear portion effecting a circulation of the pulp mass beneath the bed plate to the forward end of 15 the beater.

8. A paper pulp beater comprising a tub, a bed plate extending transversely of the tub from one side of the same to the other, said bed plate being arranged in spaced apart relationship from 20 the bottom of the tub, a beater roll rotatably mounted in the tub above the bed plate and co-acting therewith to process the paper pulp, a dam member extending across the tub forwardly of the beater roll and being provided with a surface 25 inclining upwardly from the forward edge of the bed plate, means for adjusting the upper edge

of said inclined surface relative to the level of the pulp in the tub, a guide plate extending across the tub and arranged adjacent the rear edge of the bed plate and extending upwardly therefrom for directing the pulp discharged from the beater roll upwardly into the rear of the tub, and the bottom of the tub being inclined downwardly from the rear end toward the front end to assist the flow of stock beneath the bed plate and upwardly over the upper edge of said dam member. 10

9. A paper pulp beater comprising a tub, a beater roll rotatably mounted in the tub, a bed plate arranged beneath the beater roll and being spaced apart from the bottom of the tub to permit circulation of the stock beneath the bed plate, said tub being provided with an upwardly extending rear portion provided with a curved ceiling arranged to receive the pulp discharged from between the beater roll and the bed plate in a tangential sheet, and redirect the same forcibly downward between the mass of stock in the tub and the rear end of the tub, and to effect violent agitation at the point of confluence, and means for venting said upper rear portion of the beater tub. 15 20 25

WALTER N. SHERWOOD.
